UNITED STATES PATENT OFFICE

MORRIS SPERLING, OF PORT JERVIS, NEW YORK, ASSIGNOR TO KNICKERBOCKER SILVER CO. INC., OF PORT JERVIS, NEW YORK, A CORPORATION OF NEW YORK

DESIGN FOR A CONTAINER

Application filed August 2, 1932. Serial No. 44,509. Term of patent 3½ years.

To all whom it may concern:

Be it known that I, MORRIS SPERLING, a citizen of the United States, residing at Port Jervis, county of Orange, and State of New York, have invented a new, original, and ornamental Design for Containers, of which the following is a specification, reference being had to the accompanying drawing, forming part thereof.

The figure is a side elevation of a container

which is substantially circular in cross section, showing my new design. In the drawing the substantially vertical parallel lines are shade lines representing polished surfaces; and the stippled portions represent dull roughened surfaces.

I claim:

The ornamental design for a container, as shown and described.

MORRIS SPERLING,
